DESIGN FOR A SIGNAL CHIME

Lawrence G. Bergeron, Cleveland, Ohio, assignor
to The Mello Chime and Signal Corporation,
Cleveland, Ohio, a corporation of Illinois

Application November 17, 1934, Serial No. 54,068

Term of patent 14 years

To all whom it may concern:

Be it known that I, Lawrence G. Bergeron, a citizen of the United States, residing at Cleveland, in the county of Cuyahoga and State of Ohio, have invented a new, original, and ornamental Design for a Signal Chime, of which the following is a specification, reference being had to the accompanying drawing, forming a part thereof.

In the drawing, the figure represents a perspective view of a signal chime embodying my design.

I claim:—

The ornamental design for a signal chime, substantially as shown.

LAWRENCE G. BERGERON.
